BAG FRAME LOCKING DEVICE

Howard J. Murphy, Greenwood, Mass., assignor
to United-Carr Fastener Corporation, Cam-
bridge, Mass., a corporation of Massachusetts

Application May 22, 1937, Serial No. 144,214

4 Claims. (Cl. 41—34)

My invention relates to ornamental members used particularly, though not exclusively, with a lock member for bag frame structures and the like.

5 Referring to the drawing, in which I have illustrated preferred embodiments of my invention:—
Figure 1 is a plan view of my improved ornamental member in assembly with a bag frame locking member;

10 Fig. 2 is a section taken along the line 2—2 of Fig. 1 with the ornamental member and the locking member shown in full;

Fig. 3 is a bottom view of the assembly shown in Fig. 1;

15 Fig. 4 is a section taken along the line 4—4 of Fig. 3;

Fig. 5 is a bottom plan view showing my ornamental member assembled with a modified form of construction of the locking member; and

20 Fig. 6 is a section taken along the line 6—6 of Fig. 5.

The main object of my invention is the provision of an ornamental lock operating member of simple construction which may be easily assembled as part of a locking device of the type adapted to be secured to one frame member and having a yieldable catch device which is separably engageable with a catch element on another frame member to maintain a pair of frame members in closed position in the manner familiar to those skilled in the art.

Referring to the preferred embodiment of my invention as illustrated in Figs. 1—4 of the drawing, I have shown a preferred form of ornamental member 1 assembled with a locking member 2 through means of a clamping member 3. My preferred form of ornamental member is made of ribbon-like sheet metal formed through bending a blank transversely thereof intermediate its ends to form a part of any desired shape having an operating portion adapted to be grasped by the fingers of an operator for actuating the yieldable catch device of the locking member for separating the frame members and a base means which is adapted to be clamped in assembly with the locking member. In my preferred form of ornamental member, illustrated in Figs. 1—4, the material intermediate the free ends of the member is bent into a finger-operating portion 4 of pleasing design with free end portions 5 extending inwardly toward each other beneath the finger-operating portion to form a base (Fig. 2). The outermost free ends of the end portions 5 may be separated one from another, as most clearly shown in Fig. 2.

The locking member 2, which represents one of the forms of locking member with which I have chosen to illustrate my invention, is of the type adapted to be securely assembled with a bag frame member through snapping the locking member through an opening in a wall of the frame member. The locking member 2 has a plate-like flange portion 6 at one end adapted to be disposed above the bag frame structure when the locking member is in final attached position, a base portion 7 at an opposite end from the plate-like portion 6 (Figs. 2 and 4) and a yieldable intermediate portion 8 connecting the portions 6 and 7. The plate-like portion 6 may have a downwardly-extending lug portion 9 (Figs. 2 and 15) for engagement with a cooperating fastener element on a mating frame member (not shown) to hold the frame members together. The locking member 2 has a pair of shouldered resilient attaching portions 10 (Figs. 2 and 4) extending 20 from the base portion 7 and offset laterally relative to the intermediate portion 8. As a result of the offset relation of the attaching portions and the intermediate portion, the intermediate portion is permitted to yield back and forth relative to the attaching portions for engaging and disengaging the cooperating fastener elements provided for closing the frame members. The attaching portions 10 are adapted to contract during passage of the same through an aperture 30 of a wall of a frame member (not shown) during attachment of the locking member to the frame member and then expand to engage their shoulders 10a behind material of the wall adjacent the aperture to fix the locking member in secure assembly with the frame member. 35

The clamping member 3, adapted to secure the ornamental member 4 with the plate-like portion 6 of the locking member, comprises an elongated body portion 11 which is of substantially the 40 width of the end portions 5 of the ornamental member and is provided with flange portions 12 integral with opposed longitudinal edges of the body portion 11 and extending from the body portion in substantially spaced parallel relation 45 so as to form a channel.

Assembly of the component parts of my locking device is a relatively simple matter and may be carried out through first moving the clamping member with the flange portions 12 in full open 50 position axially relative to the ornamental member to position the free end portions 5 of the ornamental member within the channel of the clamping member. Then the free end portions 5 are disposed adjacent the top surface of the 55

plate-like portion 6 of the locking member prior to assembly of the locking member with a frame member and, finally, the flange portions 12 of the clamping member are crimped inwardly by 5 any suitable tool to clamp the plate-like portion 6 and the free end portions 5 in secure assembly one with another, as most clearly shown in Figs. 3 and 4. The locking device is now complete and may be attached to a frame member in the manner hereinabove described.

Referring to Figs. 5 and 6 of the drawing, I have shown my ornamental member assembled with a modified form of locking member 13 which is preferably formed from a single piece of metal 15 and includes the clamping member and the locking member as a unit. My modified locking member 13 is adapted to be hingedly secured upon one of a pair of bag frame members and so arranged as to automatically rise and receive a 20 cooperating fastening element upon a mating frame member when the frame members are pressed together and prevent their separation until manually operated. The member 13 preferably comprises a flat body portion 14 having a 25 rear wall portion 15 integral with an edge of the body portion. Material adjacent the free edges of the wall portion 15 extends outwardly from the wall portion and then inwardly to provide loop portions 16. The free ends of the loop portions 30 16 are joined together, in my preferred form, by an intermediate connecting portion 17 extending in substantially parallel relation to the wall 15 for purposes of strengthening the hinge device. A lug 18 may extend from the wall 15 35 intermediate the loops 16-16 and engage the exposed surface of the connecting portion 17 to hold the intermediate portion in proper fixed position relative to the wall portion. The loop portions 16-16 are adapted to pass through 40 openings in the wall of a bag frame (not shown) and receive within them portions of a torsion spring (not shown) which operates to press the clasp body tightly downwardly holding a portion of the clasp in engagement with a cooperating 45 fastener element of another frame member (not shown) in a manner well known in the art.

The ornamental member, used in combination with the clasp member 13, is similar in form to the ornamental member shown in Figs. 1-4 but having relatively shorter end portions 5. In 50 order that the ornamental member may be securely assembled therewith, the clasp member of the locking device is provided, in my preferred form, with a flange portion 19 integral with the 55 entire length of an edge of the body portion 14 opposed to that from which the wall portion 15 extends and extending in substantially perpendicular relation to the plane of the body portion 14. On each side of the wall portion 15 I have 60 formed flange portions 20 extending from an edge of the body portion 14 in substantially parallel relation to the flange portion 19 whereby they cooperate with the flange 19 to form a channel. In assembling the ornamental member with the 65 clasp member 13, the free end portions 5 of the ornamental member are disposed within the channel formed by the flange portions 20 and 19 and then by any suitable tool the flange portions 20 and 19 are crimped inwardly to clamp the end 70 portions 5 in engagement with the body portion

14 so as to secure the parts in firm assembly, as most clearly shown in Fig. 6. When the completed locking device is assembled with the bag frame member, a portion of the flange 19 may provide a lip for receiving a cooperating catch element of the mating frame member for holding the frame members in closed position.

Thus by my invention I have provided ornamental members of simple construction and pleasing design which may be quickly and easily assembled with many forms of locking members to provide a compact and efficient locking device. The specific ornamental members hereinabove set forth are particularly adapted for use with locking members of the type illustrated and described, 15 but it should be understood that my ornamental members may be equally well applied to other locking members for bag frames and the like.

Although I have illustrated and described preferred embodiments of my invention, I do not 20 wish to be limited thereby because the scope of my invention is best defined by the following claims.

I claim:

1. The combination with a member of a lock 25 for bag frames having a plate-like portion of an ornamental member having an operating portion superposed above said plate-like portion and a base beneath said plate-like portion, and attaching means integral with opposed edges of said 30 plate-like portion extending in angular relation to said plate-like portion and clamping the base of said ornamental member in assembly with said plate-like portion.

2. In combination with a member of a lock for 35 bag frames having a plate-like portion of an ornamental member formed of ribbon-like sheet metal material having an operating portion superposed above said plate-like portion and inwardly-turned free end portions providing a base, 40 said base disposed beneath said plate-like portion, and flange portions integral with opposed edges of said plate-like portion engaging the base of said ornamental member to clamp said base against said plate-like portion.

3. The combination with a member of a lock for bag frames having a plate-like portion of an ornamental member having an operating portion and free end portions providing a base, said base disposed in superposed adjacent relation to said 50 plate-like portion, and a clamping member having integral flange portions extending over the edges of said base and said plate-like portion and clamping said base to said plate-like portion.

4. The combination with a member of a lock 55 for bag frames having a plate-like portion of an ornamental member formed of ribbon-like sheet metal material having an operating portion and inwardly-turned free end portions, said free end portions disposed in superposed adjacent relation 60 to said plate-like portion, and a clamping member comprising an elongated flat body portion abutting outer broad surfaces of said free end portions and having spaced outwardly-extending flange portions extending over the edges of said 65 free end portions and said plate-like portion and clamping said free end portions to said plate-like portion.
